Primary Examiner — Janice Hallmark*Assistant Examiner* — Omeed Agilee(74) *Attorney, Agent, or Firm* — Lerner, David, Littenberg, Krumholz & Mentlik, LLP(57) **CLAIM**

The ornamental design for a process plate, as shown and described.

DESCRIPTION

FIG. 1 is a front perspective view of a process plate according to our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a rear bottom perspective view thereof.

The broken lines of even length shown in the drawings depict portions of the process plate that form no part of the claimed design. The broken lines of uneven length shown in the drawings depict boundary lines that form no part of the claimed design.

1 Claim, 6 Drawing Sheets(56)
